COP FRAME

Heinrich Dersen, Krefeld, Germany

Application February 28, 1940, Serial No. 321,264
In Germany January 9, 1939

6 Claims. (Cl. 242—31)

My invention relates to improvements in cop frames, and more particularly in the construction of the thread guiding means. The object of the improvements is to provide thread guiding means which are simple in construction, and in which the reciprocating masses are exceedingly small, so that the winding efficiency is high. With this object in view, my invention consists in mounting the thread guiding means on a rotary shaft located parallel to the axis of the cop tube, the said thread guiding means comprising a sleeve slideable and non-rotatable on said shaft and carrying an operating member or members and acting on an arm rockingly mounted on said sleeve and carrying the thread guide which is adapted to move in a plane parallel to the axis of the cop frame.

For the purpose of explaining the invention several examples embodying the same have been shown in the accompanying drawings in which the same letters of reference have been used in all the views to indicate corresponding parts. In said drawings

Fig. 1 is an elevation showing the cop supporting means and the thread guiding means,

Fig. 2 is a sectional elevation on an enlarged scale taken on the line 2—2 of Fig. 1,

Fig. 2a is a sectional elevation taken on the line 2a—2a of Fig. 2,

Fig. 3 is a sectional elevation on an enlarged scale showing the mechanism for operating the thread guide, the plane of section being indicated by the line 3—3, Fig. 1,

Fig. 4 is an elevation similar to the one illustrated in Fig. 1 and showing a modification.

Fig. 5 is a sectional elevation on an enlarged scale, taken on the line 5—5 of Fig. 4,

Fig. 6 is an elevation on a sectional enlarged scale showing the operating mechanism for the thread guide, the plane of section being indicated at 6—6, Fig. 4, and

Fig. 7 is a view similar to Fig. 6 and showing a modification.

Referring now to the example shown in Figs. 1 to 3, the cop supporting means and the means for operating the thread guide are mounted in plates 40 and 41. The cop supporting means comprise a spindle 2 rotatably mounted in the plate 40 and a counterpunch 3 mounted in the plate 41, the said spindle and counterpunch 3 clamping the cop tube 39 between the same as is known in the art. The spindle 2 is adapted to be rotated from a friction disk 4 through the intermediary of gear wheels 5 and 6. Parallel to the axis of the cop tube 39 a shaft 7 is rotatably mounted in

the plates 40 and 41, which shaft is driven from the disk 4 through the intermediary of gear wheels 8 and 9. Further, a screw thread spindle 17 is mounted in the plates 40 and 41 which is driven from the shaft 14 through gear wheels 37 and 38.

On the shaft 7 a sleeve 12 is mounted which is longitudinally slideable and rotatable in unison with the shaft 7, a feather key 13 being provided which engages in a longitudinal groove 14 of the shaft 7. The sleeve 12 is made integral with a disk 10 which carries operating members 11. In the construction shown in the figures the said operating members comprise pins 42 having rollers 11 mounted thereon. On the sleeve 12 a thread-guide carrier in the form of a block 15 is loosely mounted which does not take part in the rotary movement of the sleeve 12, a bushing 18 of lubricating material being provided between the said parts to reduce friction. The block 15 is held in position on the sleeve by means of a split ring 20 clamped on the sleeve by means of screws 19. The block 15 is provided with a pair of arms 16 straddling the spindle 17, so that the block 15 does not take part in the rotary movement of the shaft 7 and the sleeve 12.

The block 15 is provided with a transverse bore 43 in which a tubular member 21 is fixed, the said member being held in position by means of a screw 22 clamping the split top part of the block 15 together. In a bushing 23 fitted in the tubular member 21 a spindle 24 is rockingly mounted which is held in position within the bushing 23 by means of a ring 33 fixed to the inner end thereof. The bushing 23 is fixed within the tubular member 21 in a suitable way for example by means of a screw 44. At its outer end the spindle 24 is formed with a head 45 to which an arm 25 is secured, which is formed with an angular portion 29 extending into position for engagement with the rollers 11. To the arm 25 a thread guide 26 is secured which, preferably, engages in a groove 28 made in the arm 25, the said thread guide and arm 25 being held in position on the spindle 24 by means of a nut 27. By the construction described the thread guide 26 and the arm 25 may be readily mounted and dismounted. To reduce friction, the bushing 23 consists of a material having lubricating property, and the spindle 24 is supported at its inner end on a ball 32.

The arm 25 is formed with a flange 31 disposed concentrically of the end of the tubular member 21, and between the said tubular member and the flange a spiral spring 30 is located which is

fixed with its opposite ends respectively to the flange and the tubular member, the said spring urging the thread guide 26 in one direction and in opposition to the action of the rollers 11 thereon. Thus the thread guide is adapted to be reciprocated by the combined action of the rollers 11 and the spring 30.

For shifting the thread guiding means longitudinally of the cop tube, the block 15 is provided with a blade 34 engaging in the screw threads of the spindle 17.

The operation of the thread guiding mechanism is as follows:

The spindle 2 is rotated from the disk 4 through the gear wheels 5 and 6, and, further, from the said disk rotary movement is transmitted to the shaft 7 and the screw threaded spindle 17. The rotary movement of the shaft 7 is transmitted to the sleeve 12 and the rollers 11 which act on the angular portion 29 of the arm 25 and impart reciprocating movement thereto and to the thread guide 26, the return movement of the said thread guide being effected by the spring 30. The block 15 does not take part in the rotary movement of the sleeve 12 because it is held in position by the arms 16 bearing on the spindle 17. As winding continues the block 15 and the thread guiding means carried thereby are slowly shifted longitudinally of the shaft 14 and the cop tube 39. The block 15, mounted as it is upon sleeve 12, carries the sleeve 12 with it in its advance upon the shaft.

The shape of the face of the portion 29 of the arm 25 which is engaged by the rollers 11 is such that uniform movement is imparted to the thread guide, and the thread is uniformly wound into a cop. Preferably the rollers 11 are disposed different distances away from the axis of the shaft 7 in such a way that at the outer end of the cop the threads of the successive layers are deposited one beside the other, the said thread guide being moved to slightly different end positions. In lieu thereof the rollers 11 may be made with different diameters.

In the construction shown in Fig. 3 two rollers 11 are provided on the disk 10. But I wish it to be understood that my invention is not limited to this construction. In Fig. 6 I have shown a modification in which three rollers 11 are provided.

In Fig. 7 I have shown another modification in which the disk 10 carries a cam disk 51 which engages a roller 36 mounted on the arm 25, 29.

In Figs. 4 and 5 I have shown another modification. The main parts of the mechanism are the same as those described with reference to Figs. 1, 2 and 2a, and the same letters of reference have been used to indicate corresponding parts. However, the mechanism for shifting the block 15 longitudinally of the shaft 7 is constructed in a different way. As shown, the screw-thread spindle 52 is non-rotatably mounted in the plates 40 and 41, and on the said spindle an internally screw-threaded disk 35 is provided which bears with its outer circumference on the surface of the cop being wound. The said disk is rotatably mounted upon an arm 53 that extends from block 15 and loosely encircles the

spindle 52. The rotation of the cop 1 is transmitted to the disk 35 which is thereby advanced on the stationary screw-threaded spindle 52 and carries along the block 15.

While in describing the invention reference has been made to particular examples embodying the same, I wish it to be understood that my invention is not limited to the general arrangement of the apparatus and the construction of its parts shown in the figures. For example, I do not limit myself to the construction shown herein in which the cop is located horizontally. Further, I do not limit myself to the construction of the mechanism for shifting the thread guiding means.

I claim:

1. In a cop frame, the combination, with means for supporting the cop tube in winding position, of thread-guiding means comprising a rotary shaft parallel to the supported cop tube, a thread-guide carrier loosely mounted on said shaft, an operating member borne by, longitudinally slideable upon, and rotatable in unison with said shaft, a thread guide rockingly mounted in said thread-guide carrier and adapted to be reciprocated longitudinally of the cop tube in response to the rotation of said operating member, and means for advancing the operating member and the thread-guide carrier in unison longitudinally of said shaft.
2. In a cop frame, the combination, with means for supporting the cop tube in winding position, of thread-guiding means comprising a rotary shaft parallel to the supported cop tube, a sleeve slideable upon and rotatable in unison with said shaft, and an operating member borne by said sleeve, a thread-guide carrier loosely mounted upon said sleeve, a spindle rockingly mounted in said carrier, a thread guide borne by said spindle and an arm extending from said spindle, the said arm having an angular portion adapted to be engaged by the operating member borne by said sleeve and through such engagement to effect the reciprocation of the spindle and of the thread guide in response to rotation of said shaft, and means for advancing said thread-guide carrier together with the sleeve upon which it is mounted longitudinally of the shaft.
3. A cop frame as claimed in claim 2, in which the said operating member includes a roller, and in which the said angular portion has a curved part engaged by said roller.
4. A cop frame as claimed in claim 1, in which a plurality of operating members are provided different distances away from the axis of said shaft.
5. A cop frame as claimed in claim 1, in which the operating member is in the form of a cam, and in which the thread guide carries a roller in position for engagement by said cam.
6. A cop frame as claimed in claim 1, in which the rotatably operating member is provided with a plurality of abutments that in the course of rotation of the member engage the thread guide carrying device at diversely situated points of engagement.

HEINRICH DERSEN.
